CHARLES HOLMES, OF BOSTON, MASSACHUSETTS, ASSIGNOR TO
CHESTER GUILD, JR., OF SAME PLACE.

Letters Patent No. 90,664, dated June 1, 1869.

IMPROVED MACHINE FOR SCOURING AND SETTING OUT LEATHER.

The Schedule referred to in these Letters Patent and making part of the same.

To all persons to whom these presents may come:

Be it known that I, CHARLES HOLMES, of Boston, in the county of Suffolk, and State of Massachusetts, have invented a new and useful Improvement in Machinery for Scouring and Setting Out Leather; and I do hereby declare the same to be fully described in the following specification, and represented in the accompanying drawings, of which—

Figure 1 is a top view,

Figure 2, a side elevation,

Figure 3, a vertical and longitudinal section, and

Figure 4, an end elevation of a scouring-carriage, and its mechanism, as improved by me.

My said invention has reference to machines of the general character, as represented in the United States patent, No. 61,182, granted to Fitzhenry and Ball, or in the United States patent, No. 61,250, granted to Buy and Fitzhenry, such machines being for scouring, "setting out," glossing, finishing, or doing general "table-work" on leather; and

My said improvements consist in a mechanism for adjusting the rubbers, or tool-carriers to their proper elevations.

Also, in a mechanism for raising either or all of the said tool-carriers, and holding such up, so that it or they may not operate on the leather while the reciprocating carriage may be in movement over the same.

Also, in the arrangement of buffers, or dampers, with the tool-carrier lifter-rods, and the rocker-plate.

Also, in the arrangement and combination of gutters, or the same and a drip-trough, or pan, with lower guides of the reciprocating carriage.

In the drawings—

A denotes the said reciprocating carriage, which is usually supported by two parallel and horizontal ways, or rails, that go between parallel guides, *a a*, *b b*, extended from the sides and upper part of the said carriage, in manner as represented in the drawings. As the surfaces in contact of these guides and rails have to be kept well oiled, to prevent friction and wear, the lubricating-fluid is liable to gather on the ends of the lower guides, and drop therefrom upon the leather while being operated on by the tools, and thereby blacken or otherwise injure it.

In order to prevent such falling of the oil on the leather or table of the machine, as the case may be, I apply to each end of each lower guide *b*, an inclined gutter, or channel, *c*, and arrange, directly underneath its lowermost or outer end, a trough, or long shallow drip-pan, or reservoir, *B*, which should be fixed either to the carriage or the slide-bar on which it rests, it being arranged so that the surplus, or waste oil received into the gutters shall, after passing through them, be discharged into and caught by such reservoir.

The tool-carriers, at one end of the carriage, are

shown at C C', each being pivoted upon a rod, *d*, extending transversely through the carriage, or from one to the other of the side plates *e e* thereof.

The lifter-rods of the said tool-carriers are shown at *f f*, they being extended through long slots in the rocker-plate *D*, which goes through the carriage, and is pivoted to the middle thereof, so as to turn on a horizontal axis.

The connecting-rod of the crank, by which a reciprocating rectilinear motion of the carriage is effected, is fastened to and projected from one end of the rocker-plate.

Encompassing each lifter-rod *f* is a strong shoulder, or head, *g*, between which and the plate is an elastic block, *h*, of India rubber, which constitutes a buffer for the plate to strike against, in order to lift the tool-carrier. This elastic buffer prevents the jar and noise which are incident to the inelastic pin, or shoulder ordinarily employed on the lifter-rod.

On the upper part of each lifter-rod, a male screw, *i*, is formed. It screws up into a block, *E*, hinged to an arm, *F*, which at its inner end is pivoted to the carriage *A*, the whole being arranged as represented.

By removing the pivot-pin *k* from the arm, such arm may be raised from between its back supports, *l l*, and used as a lever to turn the block *E* around upon the screw *i*, in order to effect the requisite vertical adjustment of the tool-carrier.

It has been found, when the screw *i* has been passed through the block without being screwed into it, and was held to it by nuts screwed upon the screw, that such nuts, with check-nuts, soon work loose, owing to the constant jar to which they are subjected while the machine was in use.

With my improvement, the adjustment of the tool-carrier being once effected, it cannot become disturbed, except the arm be first removed from pivot-pin and back supports.

To the top of the carriage, and underneath each set of such arms *F*, I apply a notched slide-bar, *G*, arranged as represented.

Figure 5 denotes a vertical section taken lengthwise of the side-bar, and also through the arms and the top of the carriage.

The bar is arranged between parallel guides, *m m*, and has an arm, *n*, extended from it, at a right angle, and at its front end.

A rod, or pitman, *o*, projecting from the said arm, in manner as shown, and going through a standard, *p*, is hinged to one end of a handle, *q*, there being at the opposite end of such handle another such connecting-rod, which is to project from the notched side of another series of arms, *F*, which is to be supposed to be applied to the carriage *A*, and to be employed in supporting another set of tool-carriers.

By laying hold of and moving the handle, an attendant may so move and adjust either or both of the slide-bars G as to cause either or each of such bars to hold in a raised position either or all of the tool-carriers beneath it; that is to say, such tool-carrier, or carriers may be so raised for the purpose of keeping its tool or their tools out of action on the leather, while the carriage may be in movement over it.

In the drawings—

R denotes the rod on which the tool-carrier springs are supported. This rod is supported, at its ends, by two blocks, S S, which are arranged in vertical guide-slots in the side-plates of the carriage A. Screws, T T, are screwed into each of these blocks, the prismatic heads r r, of these screws, being arranged directly underneath a shelf, q', projecting from the carriage.

Heretofore it has been customary to screw the screws down through the shelf and against the block S, but when the oil-catching receptacle B is applied, either to the carriage or slide, it becomes, under such circumstances, in the way, so as to prevent the screws from being easily got at for the purpose of being removed. By arranging the screw-heads underneath, and so as to abut against the shelf, access to them may be easily had at any time, to better advantage than is the case when they are over the shelf.

What I claim in the above-described mechanism, as of my invention, I would state as follows:

I claim the combination of the screw-nut, or block E, and the arm F, pivoted together and connected with the carriage, substantially as described, with the tool-lifter rod, and its screw, as set forth.

I also claim the combination of the handle q, the rod o, and the notched slide-bar G, arranged, connected, and applied to the carriage, and to the series of arms F F, of the lifter-rods, substantially as specified.

I also claim the combination and arrangement of the spouts, or gutters e, and the oil-receiver B, with the lower carriage-guides b b.

I also claim the combination of the buffers, or dampers h, with the tool-carrier lifter-rods f, and the rocker-plate D.

I also claim, when the spouts and drip-pan are employed with the lower guides of the carriage, as described, the arrangements of the heads of the screws T T beneath and against the shelf q', such being as and for the purpose set forth.

CHARLES HOLMES.
